UNITED STATES PATENT OFFICE.

WILLIAM GRIKSCHET, OF DETROIT, MICHIGAN.

PRIMING-COCK.

1,282,071.

Specification of Letters Patent.

Patented Oct. 22, 1918.

Application filed December 6, 1917. Serial No. 205,713.

To all whom it may concern:

Be it known that I, WILLIAM GRIKSCHET, a citizen of the United States of America, residing at Detroit, in the county of Wayne 5 and State of Michigan, have invented certain new and useful Improvements in Priming-Cocks, of which the following is a specification, reference being had therein to the accompanying drawings.

10 The invention relates to primers for internal combustion engines, and it is the object of the invention to facilitate the injection of the priming charge directly into the cylinder or explosion chamber. In the present state of the art it is usual to provide priming cups adapted to receive a predetermined quantity of the liquid fuel which is subsequently discharged into the cylinder upon the opening of the valve. In use, one 15 or more of the cylinders of the engine usually contains a compressed charge which when the valve is opened will blow out through the liquid, interfering with its passage into the cylinder. It also frequently 20 happens that the passage becomes clogged with carbon so that it is difficult or impossible to introduce the priming fluid. With my improvement I dispense with the cup, thereby reducing the amount of metal required and the cost of the fitting, and also 25 provide means for directly injecting the priming fluid from an oil can or other container. The construction is further one in which the passage into the cylinder or explosion 30 chamber may be readily cleaned from carbon deposit, and by inserting the spout of the can or container into this passage the fluid may be forced inward under 35 pressure.

40 In the drawings:

Figure 1 is an elevation of the construction;

Fig. 2 is a longitudinal section therethrough;

45 Fig. 3 illustrates the arrangement of the cock when placed on the side of the engine cylinder and the manner of forcing the fluid therethrough.

50 A is a fitting provided with the threaded nipple B, the polygonal portion C and the portion D beyond said polygonal portion having a lateral enlargement E. F is a bore extending longitudinally of the fitting and forming at one point therein a conical valve seat G. H is a bore at an oblique angle to

the bore F, passing through the enlargement E and having a flaring mouth portion I. The bores F and H intersect each other above the conical seat G, so that both may be closed by a single needle-valve J. This is 60 formed with a threaded stem K engaging a threaded portion of the bore F, as shown.

In machining the fitting the bore F with the conical seat therein may be formed by a single tool, and in the same manner the bore 65 H with the flaring portion I may be machined by a single tool. This will simplify and cheapen the manufacturing cost.

In use, the fitting is engageable either with a vertical aperture in the engine casing, (not 70 shown) when the valve is disposed vertically, as shown in Fig. 1, or with a horizontal aperture when disposed horizontally, as shown in Fig. 3; or it could be engaged with an aperture at any angle between these 75 two extremities. In each of these several positions the flaring mouth I of the aperture H will be so arranged that the spout of an oil can may be readily inserted thereinto and the conical or funnel-shaped wall will form 80 a guide for directing the spout into the smaller aperture. Thus the operator desiring to prime the cylinder needs only to unseat the valve J and then to insert the spout of the oil can in the funnel-shaped guide I, 85 forcing it into the aperture H and then injecting the fluid directly into the cylinder. If at any time when the engine is running it is desired to open the cock this may be done without danger of contact with the hot exhaust 90 gases, as the direction of the oblique bore H is such as to clear the handle of the valve.

It will be observed that the two intersecting bores F and H together form a Y-shaped 95 passage, the stem portion of the Y being below the valve seat G.

What I claim as my invention is:

1. A priming cock, comprising a fitting having a threaded nipple at one end thereof, 100 a portion extending outwardly therefrom, a laterally-extending portion on said outwardly-extending portion, a bore extending through said fitting axially of said threaded nipple, a valve-stem having a threaded engagement with said bore and adapted to be seated therein, a bore extending through said laterally-extending portion at an angle to said first-mentioned bore, and a flaring 105 guide at the outer end of said last-mentioned 110

bore for directing a filling spout directly thereinto.

2. A priming cock, comprising a fitting having a threaded nipple, a portion extending outwardly therefrom with a laterally-extending portion having an obliquely-extending outer face, a bore extending through said fitting axially of said nipple and having a valve seat therein, a bore extending through said laterally-extending portion at an angle to said first-mentioned bore and intersecting the same above said seat, said last-mentioned bore being substantially perpendicular to said oblique face, and a flaring

mouth portion for said oblique bore for directing a filling spout directly thereinto. 15

3. A priming cock, comprising a fitting having a threaded nipple with a passage extending axially therethrough and an oblique passage intersecting the same, a valve-stem 20 engaging said first-mentioned passage and adapted to be seated beyond the inner portion of said oblique passage, and means for guiding a filling spout directly into said oblique passage. 25

In testimony whereof I affix my signature.

WILLIAM GRIKSCHET.
